UNITED STATES PATENT OFFICE

2,415,327

DETACHABLE STEP FOR LADDERS

Robert A. Yothers, Lodi, Ohio

Application April 13, 1944, Serial No. 530,801

3 Claims. (Cl. 304—10)

1

The invention relates to steps for ladders, and more especially to a flat step arranged to be placed upon the usual rounded rung of a ladder.

Ladders, such as are used by carpenters, painters and other workmen, usually comprise a spaced pair of side rails joined at conveniently spaced points by substantially round rungs upon which the workmen are frequently required to stand for long periods of time in order to work at the desired elevation above the ground. Standing upon these round rungs is not only tiring and painful, but is often injurious to the workmen's feet.

The present invention therefore contemplates the provision of a flat step which may be detachably mounted upon any rung of a ladder upon which it may be necessary for a workman to stand for any length of time.

Another object of the invention is to provide a step of this character having means whereby it may be quickly and easily mounted upon or removed from the rung of a ladder.

A further object is to provide such a ladder step which is adjustable to various lengths of ladder rungs.

It is a still further object of the invention to provide a detachable, adjustable ladder step comprising two telescoping, flat step members with means for holding them in adjusted, extended positions and means for holding them in retracted position.

Another object is to provide a detachable step for ladders in which a U-shape attaching bracket is pivotally connected to each end of the detachable step for engagement with the side rails of the ladder, so that the step may rest in horizontal position upon the ladder rung regardless of the inclination of the ladder.

Still another object of the invention is the provision of a detachable ladder step of the character referred to, in which a hook is formed upon one end of one of the U-shape brackets, so that the detachable step may be hung upon a ladder rung or other support when not in use.

A further object is the provision of an adjustable ladder step comprising a hollow, flat sheet metal member and a solid flat member of wood, or the like, telescopically mounted therein.

It is a further object of the invention to generally simplify and improve the construction of detachable, adjustable steps for ladders.

The above objects, together with others which will be apparent from the drawing and following description, or which may be later referred to, may be attained by constructing the improved

2

detachable, adjustable step for ladders in the manner illustrated in the accompanying drawing, in which:

Figure 1 is a front elevation of a ladder showing the improved detachable, adjustable step mounted upon a rung thereof in position for use.

Fig. 2 a detached perspective view of the improved ladder step, and

Fig. 3 an enlarged transverse sectional view taken as on the line 3—3, Fig. 1.

Similar numerals refer to similar parts throughout the drawing.

A ladder of any usual and well known construction is illustrated in Figs. 1 and 3 comprising the usual spaced side rails 10 connected at intervals by the round rungs 11.

The improved, detachable, adjustable step, to which the invention pertains, comprises two flat telescoping members indicated generally at 12 and 13. The member 12 is preferably in the form of a flat, hollow sheet metal member closed at one end as at 14 and open at its other end as at 15, and the member 13, may be formed of wood or the like and is shaped to slidably fit within the hollow member 12.

A sheet of rubber matting, or the like, as indicated at 16 may be fixed upon the upper surface of the hollow member 12 to provide more sure footing as well as to add to the comfort of the workmen when standing thereon, and for the same reason, a similar sheet of rubber matting or the like, as indicated at 17, may be fixed to the top surface of the telescoping member 13.

For the purpose of preventing the member 13 from sliding relative to the hollow member 12 when the device is not in use, the side edges of the member 13 may be longitudinally grooved as at 18 and set screws or the like, preferably wing bolts as shown at 19, may be threaded through opposite side walls of the hollow member 12 and engaged in said grooves. The closed inner ends 20 of the grooves 18 will limit the outer sliding movement of the member 13 relative to the member 12, preventing the two members from becoming accidentally separated.

For the purpose of positively holding the telescoping members in adjusted position and preventing the member 13 from accidentally sliding into the member 12 when in use, a safety catch or lock may be provided in the form of a stud or pin 21 mounted upon one end of a leaf spring 22, the other end of which is attached to the top of the hollow member 12 as at 23. A button or other projection 24 is provided for manually operating the same. The stud or pin 21 is adapted

to be inserted into any one of the plurality of sockets 25 in the member 13 to hold the two members in adjusted position.

In order to detachably mount the step in adjusted position upon the rung of a ladder, substantially U-shape brackets 26 are pivotally mounted as at 27 upon the outer ends of the member 12 and 13 for engaging around the side rails of the ladders as shown in Figs. 1 and 3. As shown in these figures, the pivotal mounting of the U-shape attaching brackets 26 permit them to be swung to any angle relative to the telescoping step members 12 and 13 which may be required by the inclination of the ladder while at the same time permitting the adjustable step to rest in a horizontal position upon the rung 11 of the ladder.

If desired a hook 28 may be formed upon one of the U-shape brackets 26 so that the detachable step may be hung upon the rung of a ladder or other support when not in use.

From the above it will be obvious that a simple, strong, efficient and easily operated detachable step is provided which may be adjusted to ladders of different widths and positively held in adjusted position securely detachably mounted upon the ladder with the step in horizontal position upon any desired rung of the ladder regardless of the angle to which the ladder may be inclined.

I claim:

1. A detachable step for ladders comprising a flat, hollow member, a second flat member slidably mounted within the hollow member, means for locking said flat members in relatively adjusted position, and U-shape brackets pivotally connected to the outer ends of said flat members for engagement with the side rails of a ladder, said second flat member being longitudinally grooved to a point spaced from its inner end, and removable screw means upon the hollow, flat member engaging said groove for normally preventing complete separation of the members.

2. A detachable step for ladders comprising a flat, elongated, rectangular, hollow sheet metal box-like member closed at its outer end and open at its opposite end, and a flat, elongated, rec-

tangular, solid member slidably mounted within the open end of the box-like member, a longitudinal groove in one side edge of the solid member terminating at a point spaced from the inner end thereof, a removable stud in the adjacent side of the hollow member located in said groove to normally prevent complete separation of the two members, means for locking said members in relatively adjusted position, and U-shape brackets pivotally connected to the outer ends of the flat members for engagement with the side rails of a ladder.

3. A detachable step for ladders comprising a flat, elongated, rectangular, hollow sheet metal box-like member closed at its outer end and open at its opposite end, and a flat, elongated, rectangular, solid member slidably mounted within the open end of the box-like member, a longitudinal groove in one side edge of the solid member terminating at a point spaced from the inner end thereof, a removable stud in the adjacent side of the hollow member located in said groove to normally prevent complete separation of the two members, means for locking said members in relatively adjusted position, comprising a leaf spring fixed upon one end of the top of the hollow member, a stud upon the free end of the leaf spring and a plurality of sockets in the top of the solid member for selectively receiving said stud, and U-shape brackets pivotally connected to the outer ends of the flat members for engagement with the side rails of a ladder.
